UNITED STATES PATENT OFFICE.

GEORGE A. KNAPP, OF CHICAGO, ILLINOIS, ASSIGNOR TO KNAPP BROTHERS MANUFACTURING COMPANY, OF CHICAGO, ILLINOIS, A CORPORATION OF ILLINOIS.

SUPPORTING CLIP.

Application filed June 11, 1923. Serial No. 644,570.

To all whom it may concern:

Be it known that I, GEORGE A. KNAPP, a citizen of the United States, residing at Chicago, in the county of Cook and State 5 of Illinois, have invented certain new and useful Improvements in Supporting Clips, of which the following is a specification.

This invention relates to supporting clips for sheet metal articles.

10 One of the objects of the invention is to provide an improved supporting clip for sheet metal articles, such for example as plasterers' corner beads, and the like.

Another object is to provide a clip which 15 will have an inseparable grip on the article supported when the clip is nailed, or otherwise fixed to the wall of the building structure.

A further object is to provide a one-piece 20 clip having integral parts to hold or grip the bead without any change in the bead structure.

Other objects and advantages will herein-after appear from a consideration of the 25 following description, when taken in conjunction with the drawings, wherein:

Fig. 1 shows a perspective view of a corner bead with the clip attached thereto.

Fig. 2 is a plan view of the clip.

30 Fig. 3 is a longitudinal section of the clip.

In all the views the same reference characters are employed to indicate similar parts.

In many situations where a plaster corner 35 bead is required at the corner of a wall to serve as a ground to which the plaster is to be finished and to serve as a protecting means for the plaster, it becomes necessary to line up the projecting bead, or nose, in a vertical plane, with respect to the corner of 40 the wall structure. In such cases parts of the bead must be located varying distances from the wall and for this purpose the improved clip is especially valuable.

45 In attaching the clip to the corner bead of standard type, one of the plaster-keying holes in the side walls of the flanges, or wings of the bead, is utilized as means, in conjunction with especially formed parts of the clip, to secure the clip to the bead.

The clip is made entirely of a single strip 50 of sheet metal having a flat body part 5 with perforations 6 to receive nails to fix it to a building wall structure.

55 Near one end of the clip are slits made

from the side edges of the clip, extending inwardly and axially to form tongues 7 and 8. The tongue 7 points toward the near end 9 and the tongue 8 points toward the more remote end 10. One end of each tongue is inseparably attached to the body part 5 of the clip.

A hump 11 is formed in each tongue near its attached end to raise this portion of the tongue slightly above the underlying surface of said body part to provide space to receive the metal of the corner bead between the tongue and the body part of the clip. The free ends 12 of the tongues are slightly curved outwardly to conveniently admit the engaging part of the corner bead under the tongues.

13 is a typical corner bead structure having the usual bead 14 and the diverging side wings or flanges 15 and 16 with the plaster-keying holes 17 at intervals.

To attach the clip, it is placed below a side wing, and tongue 8 is passed thru a perforation 17. The clip body is then moved to the right until tongue 7 rides above the adjacent part of the wing 15, whereupon the clip is now moved to the left until its longest axis is substantially 90 degrees from the longest axis of the bead. When the clip is nailed to the wall, and when two or more 55 clips are used on a single bead, there can be no relative movement of the clip and bead.

It is not practicable to rivet the clip to the bead, as a shop operation, because there is no convenient way of pre-determining 60 their location and, to perform such an operation at the point of application or on the work, would be inconvenient and an expensive proceeding.

The improved clip is strong, relatively 65 thin, easily to be applied and inexpensive in construction.

Having described my invention what I claim as new and desire to secure by Letters Patent, is:

A supporting clip for sheet metal structures comprising a flat body part having two integral tongues on opposite sides near one end, each tongue having a hump near its attached end to bodily displace the tongue laterally from the body part and having its free end bent outwardly.

In testimony whereof I hereunto subscribe my name.

GEORGE A. KNAPP.
